UNITED STATES PATENT OFFICE.

WILLIAM HENRY SHAY, OF NEWBURGH, NEW YORK, ASSIGNOR TO JUDSON A. GOODRICH, OF NEW YORK, N. Y.

VACUUM-VALVE.

SPECIFICATION forming part of Letters Patent No. 677,888, dated July 9, 1901.

Application filed June 4, 1900. Serial No. 19,000. (No model.)

To all whom it may concern:

Be it known that I, WILLIAM HENRY SHAY, a citizen of the United States, residing at Newburgh, in the county of Orange and State 5 of New York, have invented a certain new and useful Improvement in Vacuum-Valves, of which the following is a description.

My invention relates to improvements in vacuum-valves adapted for use in connection 10 with automatic air-valves for steam-radiators; and the object of my invention is to provide a simple, cheap, and efficient device by means of which air will be prevented from entering a steam-radiator after the steam has been cut 15 off therefrom and has condensed, whereby a vacuum will be maintained in the radiator, so that upon again turning on the steam therein the latter will be more rapidly heated than if it were allowed to become filled with air.

20 In carrying my invention into effect I screw a cap on the nipple of any desired form of automatic air-valve and through which the air from the radiator will be expelled by the entering steam, and I provide said cap with 25 an interior valve-seat, with which co-operates an inwardly-closing vacuum-valve, preferably of the ball type, which automatically seats itself, whereby the said vacuum-valve will open outwardly to permit of the expulsion 30 of air from within the radiator, but will close inwardly as soon as the pressure within the radiator or air-valve drops below that of the atmosphere.

In order that my invention may be better 35 understood, attention is directed to the accompanying drawings, forming part of this specification, and in which—

Figure 1 is a vertical sectional view, partly 40 in elevation, showing my improved vacuum-valve applied to an automatic air-valve of a common type; Fig. 2, an enlarged sectional view of my improved device in its preferred form removed from the air-valve; Fig. 3, an interior view looking upward through the 45 cap, and Fig. 4 a section on the line 4-4 of Fig. 1 looking downward.

In all of the above views corresponding parts are represented by the same numerals of reference.

50 1 represents an automatic air-valve, which is of any suitable type and which is ordinarily provided with a float 2 and with a valve-spindle 3, co-operating with a seat 4,

whereby the valve-spindle will close upon said seat after the air has been expelled from 55 the radiator.

5 is the nipple of the air-valve, generally screw-threaded exteriorly, and engaging said threads is a cap 6, which forms the body of my improved vacuum-valve. Obviously the 60 connection between the cap 6 and the nipple 5 may be of any other desired kind. The top of the cap is provided with an opening 7 therein, through which air from the radiator and air-valve will pass. Carried within the cap 65 is a plug 8, preferably screwed in place and formed with an inclined or tapered valve-seat 9, and engaging said seat is a valve 10, which closes downward and which, by preference, is a ball-valve, as shown. Tightness 70 of joint between the cap and nipple is improved by placing a gasket-ring 11 between the bottom of the plug 8 and the top of said nipple, as shown.

In operation the turning on of steam at the 75 radiator results in the expulsion of air therefrom, which air passes through the air-valve and up through the opening in the plug 8, elevating the vacuum-valve 10 and escaping 80 through the opening 7. As soon as the valve-spindle 3 of the air-valve closes the vacuum-valve 10 will be seated. When steam is turned off from the radiator and begins to condense therein, the creation of a vacuum 85 within the radiator causes the atmospheric pressure to force the vacuum-valve 10 more firmly upon its seat, so as to prevent any passage of air into the radiator, whereby the vacuum therein will be preserved.

Having now described my invention, what 90 I claim as new, and desire to secure by Letters Patent, is as follows:

As a new article of manufacture, a vacuum-valve adapted to be attached to an automatic air-valve of a steam-radiator and comprising 95 an internally-screw-threaded cap, a plug screwed into said cap and having a tapered valve-seat, and a valve engaging said seat and located between the plug and the top of the cap, substantially as set forth.

This specification signed and witnessed this 15th day of May, 1900.

WILLIAM HENRY SHAY.
